UNITED STATES PATENT OFFICE.

ALFRED SMALLWOOD, OF HIGHGATE, LONDON, ENGLAND.

FURNACE.

1,396,943.

Specification of Letters Patent. Patented Nov. 15, 1921.

Application filed March 8, 1920. Serial No. 364,267.

To all whom it may concern:

Be it known that I, ALFRED SMALLWOOD, a subject of the King of Great Britain, residing at 42 Hargrave Park, Highgate, London, N., in the county of Middlesex, England, metallurgist, have invented certain new and useful Improvements in or Relating to Furnaces, of which the following is a specification.

10 This invention comprises certain improvements in or relating to furnaces, and is particularly applicable for the heating of long articles such as angle and channel irons for ship building.

15 According to the present invention, the air for combustion is heated by a sectional recuperator system located longitudinally below the working chamber, said recuperator system being fed by the waste gas at a plurality of points in the length of the furnace, as for instance at both ends, and at one or more intermediate positions. The cold air is also admitted to the recuperator system at a plurality of positions advantageously at 20 positions intermediately to the waste gas admission positions. Between the sectional recuperator system and the working chamber a common or sectional green gas flue is provided which is fed by a gas producer 25 or plurality of gas producers advantageously located at the side of the furnace.

In order that this invention may be clearly understood and readily carried into practice, reference may be had to the appended 30 explanatory drawings, on which:

Figure 1 is a sectional plan of a furnace constructed according to the present invention, the plane of section of the left-hand half of the figure being on line 1—2 of 40 Fig. 3, and that on the right-hand side of the figure being on line 3—4 of Fig. 3.

Fig. 2 is a sectional plan on line 7—8 of Fig. 3.

Fig. 3 is a sectional elevation of the furnace shown in Fig. 1, the plane of section being on the lines 5—6 of Fig. 1.

Fig. 4 is a part-sectional elevation of the furnace on the line 9—10 of Fig. 3.

In a convenient embodiment of the invention, as illustrated in the drawings, *a* is the working chamber and *b* is the main green gas flue which may extend the full length of the working chamber, and which is fed by two gas producers *c*, *c*. From this green gas flue at intervals around its length a

series of ports or passages *d* extend to the one side of the working chamber, these ports or passages being advantageously individually regulable. On the other side of the working chamber there are a plurality of 60 waste gas outlets *e*. There may, for instance, be one waste gas outlet at each extremity and one at a mid-position in the length of the furnace. These waste gas outlets also may be individually regulable. The waste gas 65 outlet at the mid-position in the length of the furnace may branch, as indicated at *f*, Fig. 1, and communicate by up flues *g* with two recuperator flues *h* extending in each opposite direction longitudinally of the furnace. The waste gas outlet *e* at each end of the furnace may receive the waste gas by way of a transverse flue from ports *u* in the floor of the working chamber as well as by way of the lateral outlet *v*. Each end waste 70 gas outlet *e* may communicate with two recuperator flues, as indicated at *i*, and by way of two up flues *j* extending toward the center of the furnace to a point in proximity to the termination of the flues *h* extending 75 from the central waste gas outlet, so that at positions intermediately to the waste gas outlets *e*, from the working chamber, the waste gas outlets *l*, *m* from the recuperator occur. In the vicinity of the waste gas outlets *l*, *m*, from the recuperator, the intakes 80 for cold air are provided. One *n* is provided for each half of the furnace and is adapted to branch into two up flues *s* which communicate with two longitudinal recuperator 85 flues *p* extending in opposite directions, one toward the end and the other toward the center of the furnace. At the center of the furnace the longitudinal air recuperator flues of the two half systems may, if desired, 90 be interconnected, as indicated at *q*. The said air recuperator flues *p* which are located between the waste gas recuperator flues *h* pass laterally at *r* and communicate with a side air flue *s* located on the side of the furnace on which the gas ingress ports 95 *d* occur, and from this longitudinal hot air flue passages *t* extend upwardly at intervals along the length of the furnace to supply air to the working chamber in the vicinity 100 of, and preferably above, the gas admission ports. Each ascending flue *t* may feed two ports *w*, for which purpose it may be of T-form in elevation. The air ports as well as the gas ports being individually reg-

105 110

utable, more or less heat can be imparted to any part of the working chamber, and the actual combustion may advantageously take place within the working chamber upon the admixture of the recuperated air with the green gas admitted by the gas ports leading from the main gas flue located between the working chamber and the recuperator system.

10 What I claim as my invention and desire to secure by Letters Patent is:—

1. A furnace, including an elongated working chamber, a sectionalized recuperator system arranged below said working chamber and means for admitting waste gas from different portions of said working chamber to said recuperator system at a plurality of points in the length of the furnace, the waste gas in the recuperator system flowing in opposed directions.

2. A furnace, including an elongated working chamber, a sectionalized recuperator system arranged below said working chamber, means for admitting waste gas from different portions of said working chamber to said recuperator system at a plurality of points in the length of the furnace, the waste gas in the recuperator system flowing in opposed directions and means for admitting cold air to the recuperator system at a plurality of positions intermediate the admissions of waste gas.

3. A furnace, including an elongated working chamber, a sectionalized recuperator system arranged below said working chamber, means for admitting waste gas from said working chamber to said recuperator system at a plurality of points in the length of the furnace, the waste gas in sections of the recuperator system flowing in opposed directions, means for admitting cold air to the recuperator system at a plurality of positions intermediate the admissions of waste gas, a longitudinal gas flue interposed between said recuperator system and the working chamber and in communication with the latter, and a plurality of gas producers communicating with said longitudinal flue.

4. A furnace, including an elongated working chamber, a sectionalized recuperator system arranged below said working chamber, means for admitting waste gas from said working chamber to said recuperator system at a plurality of points in the length of the furnace, the waste gas in sections of the recuperator system flowing in opposed directions, means for admitting cold air to the recuperator system at a plurality of positions intermediate the admissions of waste gas, a longitudinal gas flue interposed between said recuperator system and the working chamber, a series of ports establishing communication between said longitudinal gas flue and one side of the working

chamber, and a plurality of gas producers communicating with said longitudinal flue.

5. A furnace, including an elongated working chamber, a sectionalized recuperator system arranged below said working chamber, a series of ports extending upwardly of said recuperator system to said working chamber, to permit admission of waste gas to said recuperator system at a plurality of points in the length of the furnace, the waste gas in sections of the recuperator system flowing in opposed directions, means for admitting cold air to the recuperator system at a plurality of positions intermediate the admission of waste gas, a longitudinal gas flue interposed between said recuperator system and the working chamber and in communication with the latter, and a plurality of gas producers communicating with the longitudinal flue. 85

6. A furnace, including an elongated working chamber, a sectionalized recuperator system arranged below said working chamber, a series of ports extending upwardly of said recuperator system to said working chamber to permit the admission of waste gas to said recuperator system at a plurality of points in the length of the furnace, the waste gas in sections of the recuperator system flowing in opposed directions, means for admitting cold air to the recuperator system at a plurality of positions intermediate the admissions of waste gas, a longitudinal gas flue interposed between said recuperator system and the working chamber, 100 a series of ports interconnecting said flue and said working chamber, and a plurality of gas producers communicating with said longitudinal flue.

7. A furnace, including an elongated working chamber, a sectionalized recuperator system arranged below said working chamber, a series of individually regulable ports extending upwardly of said recuperator system to said working chamber, to permit admission of waste gas to said recuperator system at a plurality of points in the length of the furnace, the waste gas in sections of the recuperator system flowing in opposed directions, means for admitting cold air to the recuperator system at a plurality of positions intermediate the admission of waste gas, a longitudinal gas flue interposed between said recuperator system and the working chamber and in communication with the latter, and a plurality of gas producers communicating with the longitudinal flue. 110 120

8. A furnace, including an elongated working chamber, a sectionalized recuperator system arranged below said working chamber, a series of ports extending upwardly of said recuperator system to said working chamber to permit the admission of waste gas to said recuperator system at a plurality of points in the length of the fur- 125 130

nace, the waste gas in sections of the recuperator system flowing in opposed directions, means for admitting cold air to the recuperator system at a plurality of positions intermediate the admission of waste gas, a longitudinal gas flue interposed between said recuperator system and the working chamber,

a series of individually regulable ports interconnecting said flue and said working chamber, and a plurality of gas producers communicating with said longitudinal flue. 10

In witness whereof I have hereunto set my hand.

ALFRED SMALLWOOD.
